PNEUMATIC PERCUSSIVE TOOL

Georges Brun, Saint-Etienne, France, assignor
to Société d'Etudes et d'Exploitation du Gé-
nérateur à Piston Libre, a corporation of France

Application January 23, 1935, Serial No. 3,138
In France January 23, 1934

8 Claims. (Cl. 121—30)

The present invention relates to a pneumatic tool which can be used for the most varied purposes (piercing, cutting, riveting, etc.) and which is very powerful and highly efficient in operation.

5 The power of usual pneumatic tools is limited because the speeds of the piston at the moment of impulse must not exceed three to four meters per second and on the other hand the efficiency is low.

10 Experience has shown in fact that the best steels known only withstand repeated impacts if the speed of impact does not exceed the above stated limit.

Further, the efficiency is low chiefly because 15 a great part of the kinetic energy of the piston is destroyed through the impact by the elastic hysteresis and unnecessary vibrations and in addition on account of the fact that the distribution of compressed air motors is of an elementary 20 nature.

In practice with a bore of 40 to 50 m/m. for 25 the air cylinder (tools working in all directions) useful powers are obtained of 20 to 30 kg. at the point of the tool. With bores of 60 to 75 m/m. (piercing tools working in a downward direction) the useful power reaches 40 to 50 kg. The consumption of compressed air corresponds to a 30 pneumatic power which is 5 to 10 times greater.

In the tool according to the invention, a column 35 of liquid, for example oil, is interposed between the piston moved by the compressed air and the tool at the moment of impulse, the volume of this liquid being calculated in such a way that the pressures will be limited by the compressibility of the oil to admissible values.

The speed of the compressed air piston at the 40 moment of impulse may be raised to 20 meters per second instead of 4 m/m. per second, which is the limiting value in the case of direct impact.

45 The limiting power for a given recoil is thus multiplied by five.

Further, the oil interposed between the air piston and the tool holder forms a perfect spring 50 having no hysteresis and the period of vibration of the system is much higher than the period of vibration proper of the air piston and of the tool holding piston. The energy dissipated by unnecessary vibrations is greatly reduced and the efficiency is considerably increased.

In this way very handy tools can be constructed having a useful power reaching several hundred kg.

The principle of the tool according to the 55 invention will be more clearly understood by

referring to the diagram illustrated in Figure 1 of the accompanying drawings.

The main piston comprises a large diameter head a^1 , movable in a cylinder b provided with admission orifices b^1 and exhaust orifices b^2 and a 5 plunger piston of small diameter a^2 movable in a cylinder c co-axial with the cylinder b . The piston carrying tool d slides in the front end of this same cylinder c . The cylinder c passes through a chamber e from which leads a duct f which communicates with a bore g in which slides a block h . The space comprised between the piston a^2 , the tool holder d and the block h is filled with oil; the face of the block opposite that which is in contact with the oil is subjected to 15 the pressure of the compressed air.

The operation is as follows: when the piston a^1 , a^2 , is at the left-hand end of its stroke and the admission orifice b^1 is open, the piston a accelerates in a forward direction. As long as 20 the plunger a^2 has not passed beyond the chamber e the oil will be displaced in the duct f and move the block h against the pressure of the compressed air. At the end of a certain travel the piston a^2 travelling at full speed passes beyond the chamber e . The oil interposed between 25 a^2 and the tool holder d is violently compressed while the speed of the piston a^1 , a^2 , slackens and the tool holder d receives the impulse which causes it to advance against the work piece which 30 is opposed to it.

In the meantime the admission has closed and the exhaust orifices have opened. When the piston a has come to rest it is driven backwards (the returning means are not shown in the drawings) and the operation continues as before.

It is quite natural to use the movement of the block h for the distribution of the compressed air. For this purpose the orifice b^1 leads into the wall of the cylinder g . They are covered 40 by the block h when the forward stroke of the piston has reached a suitable value and are uncovered in the opposite direction through the backward stroke when the piston is sufficiently close to the end of the cylinder b .

The construction of a tool of this type gives rise to a certain number of difficulties which necessitate the use of special devices that will be enumerated hereinafter before proceeding to the detailed description.

1. It is necessary in spite of leakages to maintain a certain quantity of oil between the pistons a^2 , d and h ; for this purpose, a reservoir of oil under pressure or feeder must be provided and also means of communication between the feeder 55

and the chamber defined above, such that at the end of the backward stroke of the main piston the block *h* will abut against the front end of the cylinder *g* without vacuum being produced.

5 2. The oil delivered by the piston *a*² before the impact is driven forward by the latter its inertia damps the forward stroke and a great part of the corresponding kinetic energy is lost. It is therefore of interest to reduce to a minimum the inertia 10 of the column of oil comprised between the chamber *f* and the block *h*. In the machine described in detail hereinafter a differential piston has been arranged in the immediate neighbourhood 15 of the chamber *f* which differential piston reduces the volume of oil delivered to the sliding block *h* to a fraction of the volume of the oil delivered by the piston *a*².

3. The sliding block *h* as described above has a movement which synchronizes with that of the 20 piston *a*¹. Under these conditions the admission opens upon the backward stroke and closes upon the forward stroke for the same position of the piston. The anticipated admission equals the true admission, it being understood that the term 25 "anticipated admission" implies the stroke of the piston in front of the rear dead point from the position where the admission is open up to said point and the term "true admission" implies the stroke of the piston after it has reached the rear 30 dead point from the latter to the position where the admission closes. It is of interest to reduce the anticipated admission with respect to the true admission and therefore to displace the movement of the sliding block so as to make it lag behind 35 the movement of the main piston.

4. It is necessary to provide an admission of compressed air against the forward face of the piston *a*¹ at the commencement of the backward stroke and also to provide distribution means. 40 In the machine described in detail hereinafter this distribution is automatic.

5. The tool holder is provided with an abutting collar which limits its displacement forwardly with respect to the body of the tool. It is necessary 45 that the space between this collar and the front end of the tool is filled with oil so that in case of an abnormal displacement forwardly of the tool holder, as when the resistance to the forward movement of the tool holder is negligible, 50 the impact of the collar against the end of the tool body is damped during the expulsion of the oil.

6. In the hydraulic transmission tool, as compared to direct impact tools, the position of the 55 main piston at the moment of impulse is unvarying; it is the position for which the plunger *a*² is flush with the forward edge of the chamber *e*. In direct impact tools the forward displacement of 60 the shank of the tool is utilized in the idle operation (without opposed resistance) in order to damp the kinetic energy of the air piston by the compression of the air between the front face of this piston and the front end of the air cylinder, 65 and these tools operate without impact on no load. In the hydraulic transmission tool, if the admission were maintained constantly on no load violent compressions would be produced between the piston *a*² and the tool holder locked against 70 the forward abutment. In order to avoid this, an automatic stopping device must be provided which cuts off the admission of compressed air when the tool holding piston approaches its forward abutment. (Such devices are not novel and are 75 provided upon certain direct impact piercing ham-

mers but they are indispensable in a hydraulic transmission tool.)

7. Finally, in the diagram shown in Figure 1 the same diameter has been given to the piston *a*² and to the tool holding piston *d*. It may be of advantage to give the piston *d* a larger diameter than the piston *a*² in order to increase the instantaneous forces and the weight of the tool without rendering the main piston heavier. This latter arrangement is that of the machine described in detail hereinafter. It does not increase substantially the recoil of the machine when the tool is free, or advances rapidly, provided that the weight of the tool is properly adjusted, but it enormously increases the recoil when the tool is locked or advances slowly, as a consequence of reactions upon the annular end of the bore of the tool holding piston while the piston *a*² rebounds upon the column of oil. In order to prevent the tool from becoming blocked under these conditions, when the resistance is too high according to the invention, a so-called recoil piston is keyed upon the tool holding piston. This recoil piston is movable in a cylinder fixed to the body of the machine and is subjected to the pressure of compressed air on its front face and to atmospheric pressure on its back face. In this way the recoil is balanced if the tool is jammed; if it is not jammed it is separated at the moment of impulse from the material acted upon so that it acts as a free tool and the recoil remains weak.

There are obviously many ways of carrying out these various conditions. By way of example one particular embodiment will be described hereinafter but it is understood that the invention may include other modifications of detail.

Figure 1 is a diagrammatic view of a machine for carrying out the principle of the invention.

Figures 2 and 2A illustrate a general section 40 of the machine, the section being shown in such a way as to make all the essential details appear.

Figure 3 is an enlarged detail view of the plunger *II* and the re-feeding valve.

Figure 4 is an enlarged section of the double 45 valve interposed between the slide valve and the differential member.

In these figures, 1 is the compressed air cylinder, with the admission orifices *1*¹ for accelerating the piston, the exhaust orifices *1*² and the admission orifices *1*³ for the return. In this cylinder reciprocates the air piston *2*¹, which is rigid with the plunger *2*² slidably mounted in the sleeve 3 which is co-axial with the cylinder 1. This sleeve communicates with the large chamber filled with oil comprised between the parts 7 and 4 (engaged in the body of the machine). The member 4 is provided with a bore 4' therein coaxial with the plunger *2*² and of the same diameter. The bore 4² is a counter bore also 60 coaxial with the plunger *2*².

When, at the end of the forward stroke the plunger *2*² engages in the bore 4¹, it violently compresses the oil interposed between the piston *2*² and the piston 5 and imparts an impulse to 65 this piston. Apart from this stage which is of short duration, the piston *2*² is not engaged in the bore 4¹ and in delivering or drawing in oil, it produces the reciprocation of the annular differential piston 6 which closes the oil chamber 70 at the back. The section 6¹ of this piston towards the front is much greater than the section of the plunger *2*² in order to reduce the inertia and the absolute displacements of the differential piston 6. Towards the back, the differential pis- 75

ton 6 has an annular face 6³ in open communication through orifices 7¹ with the feeder 8 which will be described hereinafter and an annular face 6², the section of which is only a small fraction 5 of the face 6¹ ($\frac{1}{3}$ to $\frac{1}{5}$). By means of this face 6² sliding in the bore 7² the differential piston delivers a volume of oil proportional to the displacement of the main piston through the large duct 7⁴ to the slide valve 9 (through the valves 12, 10 13, the function of which will be described hereinafter). The inertia of the column of oil interposed between the slide valve 9 and the main piston is thus considerably reduced.

The feeder will now be described: the latter is 15 a reserve of oil maintained at the pressure p of the compressed air in 10 in front of the slide valve 9. It is lodged in a chamber 8² of the tool body, communicating through ducts 15 with the pressure p . The reserve of oil is separated 20 from the air by the diaphragm 8¹ made of flexible rubber which is not attacked by oil. The pressure of the oil is thus maintained equal to p ; as the reserve of oil becomes exhausted the diaphragm is deformed accordingly.

25 The feeder at the same time as it absorbs and restores periodically a greater part of the oil delivered by the piston 2² maintains a full supply of oil between the differential piston, plunger 2² and tool holder and also between the differential 30 piston 6 and the slide valve. In the event of a lack of oil between the differential piston, plunger 2² and the tool holder, the differential piston abuts forwardly against the member 4. In this 35 position it uncovers at the rear the grooves 7⁵ which put the above described space and the feeder into communication with each other so that a vacuum cannot be produced.

On the other hand, in the event of an excess of oil the differential piston abuts at the rear against 40 the end of the bore 7² and at the front uncovers the grooves 7⁶ through which the excess of oil delivered by the plunger 2² goes to the feeder.

A description will be given hereinafter of the 45 manner in which the feeder ensures a full quantity of oil between the differential member 6² and the slide valve 9. The feeder 8 must be recharged periodically. It is easy to dimension it so that the provision of oil will be amply sufficient for eight hours of uninterrupted working.

50 The slide valve and the arrangements adopted for regulating the admission will now be described. It will be assumed that when the piston 2 is at the end of its backward travel the slide valve 9 abuts at the front against the rear face 55 of the seat of the member 12 without vacuum being produced (hereinafter a description will be given of the means of communication between the feeder and the chamber interposed between the slide valve and the differential member which permits this result to be obtained very simply). In this position the slide valve uncovers the outlet of the orifices 11 in the bore 10; the admission being wide open.

If the walls of the chamber comprised between 60 the end of the bore 7² and the end of the bore in the slide valve were indeformable, the stroke of the slide valve would be synchronous with, and opposed to, that of the piston 2 and, as explained above, the anticipated admission would 65 equal the true admission. In order to adjust the true admission to a value higher than the anticipated admission it is sufficient for the capacity defined above to increase by a certain value at the commencement of the forward stroke and to 70 fall by the same value at the commencement of

the backward stroke. Under these conditions the 75 slide valve which has come into abutment at the commencement of the forward stroke of the piston 2 will remain stationary while the increase is produced in the chamber and the true admission stroke will be increased relative to the anticipated admission stroke by the displacement of the piston 2² corresponding to the additional volume delivered by the differential member 6². 10

This increase in capacity at the commencement of the forward stroke will be obtained in the following manner: A double valve 12, 13 is interposed between the differential member 6² and the slide valve 9. The valve 12 which is pushed backwards by the spring 12¹, produces a given loss of charge, upon the passage of oil from the slide valve to the differential, which loss of charge is moreover small. As the slide valve 9 is subjected on its back face to the 20 pressure p of the compressed air, the oil pressure on the differential member 6² during the backward stroke of the main piston (the oil then goes from the slide valve to differential member) is p — the said loss of charge (approximately in view of loss of charge and inertia effects). During the forward stroke of the main piston the oil passes from the differential member 6² to the slide valve. The valve 12 is then 25 pressed upon its seat; the oil passes through the orifices 12² and lifts the valve 13 which is movable within the valve 12 and is strongly loaded by the spring 13¹. This valve 13 produces a greater loss of charge and the oil pressure at the differential member is p + the loss of charge. 30

In order to produce a required increase of capacity it is sufficient to interpose between the feeder at the pressure p and the chamber 7³ into which the bore 7² leads, a piston movable 35 between two stops.

This piston will move automatically against the pressure of the feeder at the commencement of the forward stroke and against the pressure of the oil in 7³ at the commencement of the backward stroke.

40 This piston is illustrated at 11, Fig. 3; it slides in the bore 11² formed in the ring which separates the chamber 7³ from the feeder and its stroke is limited by two stops. It is pushed forward against the pressure in the chamber 7³ 45 by a spring 11¹, Fig. 2 which balances a pressure p ¹ such that p + p ¹ will be the mean of the pressures p modified, as described by the action of the valves 12 and 13.

A description will now be given of the means 50 employed for keeping the chamber between the slide valve and the differential member full of oil by ensuring that at the end of the backward stroke of the main piston the slide valve will abut at the front against the seat of the valve 12. 55

The chamber 7³ communicates with the end of the bore 7 (that is to say with the feeder since the end of this bore communicates with the feeder through the orifices 7¹) through an orifice closed by an automatic valve 14, which lifts 60 against the reaction of the spring 14² in order to allow oil to pass from the feeder to the chamber 7³.

The wall of this valve is provided with orifices 65 14¹. As the mean pressure in the chamber 7³ 70 is greater than p during a double stroke, that is to say, a forward and backward stroke of the slide valve a small quantity of oil escapes through the orifices 14¹ to the feeder, thereby ensuring that the slide valve 9 will abut against the seat 75

of the valve 12 a little before the end of the backward stroke.

A vacuum can, moreover, not be produced because the valve 14 then lifts and the feeder restores the oil which has escaped through the preceding double stroke.

A description will now be given of the means employed for ensuring the return of the main piston. An account has been given above of the manner in which the admission by the forward stroke was regulated to a fixed value.

A certain time after the slide valve has closed the admission, the piston 2¹ in moving forward closes the exhaust orifices 12 at the front and 15 commences to compress the air between its front face and the front end of the cylinder 1.

A short time later it uncovers the orifices 12 at the rear and the pressure falls rapidly behind the piston 2¹. Finally, a little time afterwards, the plunger 2² engages in the bore 4¹ and is rapidly damped by the compression of the oil between 2² and 5. The piston 2 then stops. The expansion of the air between the front face of 2¹ and the end of the cylinder 1 and also 25 if desired the rebound of the piston 2² on the compressed oil (the latter effect moreover being variable according to the resistance opposed to the tool) tend to return the piston 2 backward but these two effects are insufficient to ensure a 30 considerable stroke backwards.

The energy stored by the compression between the front end of the cylinder 1 and the piston is in fact constant in absolute value while the energy supplied to the piston through the forward 35 stroke depends upon the pressure p .

If this pressure falls the kinetic energy of the piston 2 may be absorbed by the compression of the air at the front end and the machine would cease to produce a useful effect.

40 It is, therefore, practically necessary to admit compressed air at the commencement of the backward stroke between the front end of the cylinder 1 and the piston 2. This admission is ensured as follows on the machine described.

45 The admission orifices 13 at the front of the cylinder lead into a chamber 16⁴ separate from the chamber 15² in which the pressure p exists by means of a valve 16. The valve is formed by an internal section S₁ and a cylindrical guideway 16² sliding in a bore of section S₂ a little less than S₁ which bore communicates with the atmosphere. The spring 16¹ having a force F tending to hold the valve on its seat together with the force $p(S_1 - S_2)$ exerted upon the annular face 16³.

50 The valve is also subjected to the pressure which exists in the chamber 16⁴ by its face S₁. It lifts when this pressure reaches a value p'' such that $p''S_1$ is greater than $p(S_1 - S_2) + F$. The chamber comprised between the exhaust orifices 12 and the front end of the cylinder and the chamber comprised between this same end and the front face of the piston at the moment when 55 the plunger 2² engages in the bore 4¹ are calculated in a ratio such that the pressure between the piston and the front end of the cylinder exceeds p'' a little before this moment.

60 The valve 16 therefore lifts at the end of the forward stroke of the piston 2 and then remains raised through the commencement of the backward stroke until the piston 2¹ uncovers the orifices 12 at the back (the pressure in the chamber 16⁴ then falls below p'' and the valve falls back).

65 A description will now be given of the particular

arrangements of the tool holding piston. In front of the piston 5 engaged in the bore 4² this piston comprises a collar 5¹ which moves in a chamber 5³ filled with oil (it communicates through the perforations 4⁴ with the rear face 5 of the member 4). This collar abuts forwardly against the end of the bore 17¹ and at the rear against the end of the bore 4³. The diameters of these bores have been adjusted so as to be slightly greater than the diameter of the collar 5¹ so that the tool holding piston will be braked progressively before abutting either at the front or at the back. Shocks will thereby be avoided which may be produced either when the tool receives an impulse towards the front without encountering a sufficient resistance or when it rebounds backwards.

To the front of the collar 5¹ the tool holding piston comprises a cylindrical bearing sliding in the bore in the member 17 and passing through the stuffing box 17².

The arrangements employed for reducing the recoil are constructed in the following manner:—

Upon the tool holding piston in front of the member 17 is screw-threaded a piston 24 movable in the bore 23² of the member 23 screwed upon the body of the machine. The rear face of this piston is placed at atmospheric pressure through the orifices 23³. The front face is subjected to the pressure p through the duct 15⁵. The reaction thus produced upon the body having the effect of reducing the recoil.

Only the arrangements provided for automatically stopping the tool under no load have now to be described. They consist in cutting off the supply of compressed air when the tool holding piston advances a certain distance from its rear abutment. For this purpose, the chamber 10 in which the pressure p exists can be separated from the chamber 19 into which the compressed air duct 22 leads by means of the cylindrical slide valve 18. This slide valve comprises two cylindrical seatings 18¹, 18² of the same diameter connected together by a central rod. The outer face of the seating 18¹ is subjected to atmospheric pressure.

55 A spring 18³ bears upon this face and tends to press the slide valve against the seating 18⁵. In this position the seating 18¹ covers the opening through which the chamber 10 communicates with the bore of the slide valve 18 and cuts off the admission.

The slide valve 18 opens the admission when it has effected a certain stroke towards the rear against the reaction of the spring. The outer face of the seating 18² communicates on the one hand through the small orifice 18⁴ with the compressed air and on the other hand through the duct 18⁶ with a chamber 23¹ formed in the bore which guides the tool holder forward of the member 23.

60 The tool holder which slides in this bore has a circular groove 5² which is entirely covered by the part 23 when the tool holder is against its rear abutment and which is uncovered at the front and puts the chamber 23¹ into communication with the atmosphere when the tool holder is pressed against its front seating.

65 In this position the pressure against the face 18² falls to atmospheric pressure, the orifice 18⁴ being much smaller than the leak orifice formed by the duct 18⁶ and the space comprised between the groove 5² and the bore of the part 23.

70 The slide valve 18 under the action of its spring 18³ comes into contact with its abutment 18⁵ and 75

the admission of compressed air is cut off. On the contrary, when the tool holder is pressed against its rear abutment the leak orifice is closed, the pressure rises under the face 18² 5 and the slide valve 18 opens for the admission of compressed air.

This automatic stopping device operates at the same time as a regulating device. When the tool holder advances too quickly or when the operative does not balance the recoil of the machine at full power the tool holder automatically commences to move about the position which uncovers the groove 5² at the front. The slide valve 18 moves about the position which opens 10 the admission and the latter is throttled so that the recoil of the machine balances the effort applied to the body by the operative.

This leads to the provision of a compressed air relay between the two members and the arrangement described above is obtained in this way.

Naturally, means are provided upon the apparatus for permitting it to be handled and used.

What I claim is:—

- 25 1. A pneumatic tool comprising a body having fluid filled bores, a cylinder in said body having an admission orifice, a piston movable by compressed air in said cylinder, a tool holding piston movable in one of said bores, a plunger piston rigid with the first mentioned piston and movable in another of the fluid filled bores, a discharge chamber having an outlet end, the second mentioned bore leading to the bore of the tool holding piston and traversing said discharge 30 chamber, the outlet end of said chamber being closed by the plunger piston at the end of its travel and the fluid then interposed between said plunger and the tool holding piston being limited, a displaceable member, said body having a chamber 35 receiving said member and communicating with said admission orifice, said member constituting a slide valve for said orifice, and means connecting said discharge chamber with the second mentioned chamber whereby the fluid 40 drawn in and delivered by the piston plunger in the discharge chamber displaces said member.
2. A pneumatic tool as claimed in claim 1 characterized by the provision of a fluid containing chamber in said body, an impervious elastic diaphragm constituting a part of the wall of said fluid containing chamber, and means for subjecting the diaphragm to air pressure.
3. A pneumatic tool as claimed in claim 1 characterized by the provision of a fluid containing chamber in said body, an impervious elastic diaphragm constituting a part of the wall of said fluid containing chamber, and means for subjecting the diaphragm to air pressure, a differential piston actuated by the fluid drawn in 45 and delivered by the piston plunger in the discharge chamber, said differential member having one side presented to the discharge chamber and having two faces on the opposite side thereof, the total area of the two faces being equal 50 to the total area of the first mentioned side of the differential member, one of said faces being exposed to the fluid contained in said fluid containing chamber and the other face being of smaller area than the first mentioned face and adapted to move fluid toward and away from said displaceable member, and means acting when the differential piston is at the ends of its travel to open communication between the discharge chamber and the fluid containing chamber.
- 75 4. A pneumatic tool as claimed in claim 1 characterized by the provision of a fluid containing chamber in said body, an impervious elastic diaphragm constituting a part of the wall of said fluid containing chamber, and means for subjecting the diaphragm to air pressure, a regulating slide valve movable in said admission orifice in advance of the displaceable member with reference to the direction of flow of air,

characterized by the provision of a fluid containing chamber in said body, an impervious elastic diaphragm constituting a part of the wall of said fluid containing chamber, and means for subjecting the diaphragm to air pressure, a differential piston actuated by the fluid drawn in and delivered by the piston plunger in the discharge chamber, said differential member having one side presented to the discharge chamber and having two faces on the opposite side thereof, the total area of the two faces being equal to the total area of the first mentioned side of the differential member, one of said faces being exposed to the fluid contained in said fluid containing chamber and the other face being of smaller area than the first mentioned face and adapted to move fluid toward and away from said displaceable member, and means acting when the differential piston is at the ends of its travel to open communication between the discharge chamber and the fluid containing chamber, a double automatic valve interposed between the differential piston and said displaceable member, said double valve producing a fixed loss of charge upon the passage of the fluid from the displaceable member to the differential piston and a higher loss of charge upon the reverse passage of fluid from the differential piston to the displaceable member, a passage in said body connecting the differential piston and the fluid containing chamber, a piston having limited movement in the last mentioned passage, a passage of reduced area for the passage of fluid between the fluid containing chamber and the space between the differential piston and the displaceable member, and a valve controlled passage arranged to permit passage of fluid from the fluid containing chamber to the space between the differential piston and the displaceable member but obstructing the passage of fluid in the opposite direction.

5. A pneumatic tool as claimed in claim 1 characterized by the provision of air orifices at the front end of said cylinder, a valve normally closing said orifices, a spring normally tending to close said valve, said valve being also subjected to air pressure from the air supply to said cylinder whereby said valve is normally held in closed position.

6. A pneumatic tool as claimed in claim 1 characterized in that said tool holding piston includes a collar, a fluid filled chamber in said body receiving said collar and having walls constituting stops for the tool holding piston, said walls having grooves therein of slightly greater diameter than said collar for receiving the latter in the opposite positions of the tool holding piston.

7. A pneumatic tool as claimed in claim 1 characterized by the provision of a damping piston rigid with the tool holding piston, a chamber in said body receiving the damping piston having communication with the atmosphere at the rear of said actuating piston, and means for supplying compressed air to the front face of the damping piston.

8. A pneumatic tool as claimed in claim 1 characterized by the provision of a fluid containing chamber in said body, an impervious elastic diaphragm constituting a part of the wall of said fluid containing chamber, and means for subjecting the diaphragm to air pressure, a regulating slide valve movable in said admission orifice in advance of the displaceable member with reference to the direction of flow of air,

spring means normally tending to move the regulating slide valve to a position to close passage of air to the displaceable member, means for admitting air pressure to the regulating valve to 5 overbalance the spring means and move the latter in the opposite direction, a tool guide, an outlet element movable in said guide and having

a groove, therein, means communicating with the air admitted to the regulating slide valve and connected with said guide whereby in one position of the tool the groove therein establishes communication between the last mentioned communicating means and the atmosphere. 5

GEORGES BRUN.
